VESTIBULE SIDE CHARGER FOR CUPOLAS

John F. Drake, Los Angeles, Calif., assignor of
one-half to Theodore G. Kennard, Glendora,
Calif.

Application August 6, 1951, Serial No. 240,555

3 Claims. (Cl. 214—18)

1

This invention relates to a device for charging a shaft type or cupola furnace and in particular to a gas sealed side charging device particularly adapted for use on a closed top cupola. The principal object of the invention is to provide means for charging a cupola through a side opening without allowing the escape or dilution with air of combustion gases. Another object is to provide a side charging vestibule for a cupola which permits charging of bucket mixed charges, using standard mechanical elevating equipment. These and other objects are attained by my invention which will be understood from the following description, reference being made to the accompanying drawings in which:

Figure 1 is an elevational view partly in section showing a preferred form of my charger as mounted on a closed top cupola, only the upper portion of the cupola being shown;

Figure 2 is a horizontal sectional view of the same taken on the line 2—2 of Fig. 1;

Figure 3 is a fragmentary sectional view taken on the line 3—3 of Fig. 1;

Figure 4 is an elevational view partly in section showing another form of my invention;

Figure 5 is a horizontal cross-sectional view taken on the line 5—5 of Figure 4;

Figure 6 is a fragmentary cross-sectional view on the line 6—6 of Fig. 4 showing the sealing arrangement on the charger boom; and

Fig. 7 is a fragmentary cross-sectional view taken on the line 7—7 of Fig. 4.

Referring to the drawings, the upper portion of a cupola furnace 11 consists of a cylindrical steel shell 12 which is lined with fire brick 13. A charging opening 14 is provided on one side of the cupola near the top, and a rectangular vestibule 15, preferably also lined with brick extends outwardly toward the charger arm 16 of the boom 17 of a mechanical charger such as an inclined skip hoist or crane hoist (not shown). The steel shell of the vestibule 15 is attached to the steel shell 12 of the cupola and a vertically sliding door 18 of steel plate lined with fire-brick is provided at the outer opening of the vestibule 15, which door may be raised in the upright channels 19 by means of the chain 20, hoisting means of suitable type (not shown) being provided. An offset 21 corresponding to the vestibule 15 is provided in the side of the cupola opposite the vestibule 15, being formed of steel plate with brick lining, and being closed by a back wall 22. A pair of rails 23 are provided in the vestibule 15 and extending across the cupola, being supported on the lower edge of the offset 21 and on the floor 24 of the vestibule.

2

A charging car 25 is provided which is adapted to ride by wheels 26 on the rails 23, the car bottom being open so that the charging bucket 27, having a pivoted bottom 28, may discharge its contents into the cupola by the tilting of said bottom. The tilting of the bucket bottom on the pivot 29 may, for example, be brought about by the tilt rods 30 extending horizontally from the tilting levers 31 on the two sides of the bucket 27 against the back wall 22 when the charging car 25 is propelled into the cupola from the vestibule 15. The charging car 25 is provided with a closing wall 32 on its end adjacent the offset 21, which wall serves to close the cupola end of the vestibule 15 when the charging bucket is empty and ready to be picked up by the fork 33 of the boom 17, which fork is adapted to engage the trunnions 34 on the bucket. The charging car 25, after discharging, is pushed back into the vestibule by the rack 35 which is attached to the closing wall 32 and is actuated by the pinion 36 driven by the reversible motor means 37.

The manner of operating my vestibule charger arrangement will be clear from the above description. Assuming that a charge has just been unloaded from the bucket 27 on the car 25 (as shown in Fig. 1), the rack and pinion mechanism or its equivalent pushes the car 25 into the vestibule 15, the closing wall 32 on the car being pushed into the cupola charging opening 14 and sealing off the vestibule 15. The vestibule door 18 is then opened and the empty bucket 27 is picked up on its trunnions by the fork 33 on the charger boom 17. After the bucket has been loaded and returned through the open door 18 and placed on the car 25, the door 18 is closed and the rack 35 is retracted by the pinion 36 until the closing wall 32 is in the offset 21. Meantime the tilt rods 30 have abutted the back wall 22 and the bottom 28 of the bucket 27 has been tilted and the charge discharged into the cupola.

In the alternative form shown in Figs. 4 to 7, the charging bucket is suspended from a telescoping boom arm instead of being placed on the reciprocating car riding on rails spanning the cupola. In this form a vestibule 15A is provided near the top of the cupola, extending from a side charging opening 14. The vestibule door 18A is hinged at the outer edge of the floor 24 of the vestibule, and swings outwardly to a horizontal position to open the vestibule. A notch 40 is provided at the upper edge of the door to go around the boom 17A. The boom 17A is provided with sealing flange 41 which closes the opening or notch 40 when the bucket is in the cupola.

The boom 17A, at its free end, is provided with an inside telescoping member 17B, at the end of which is provided a notched extension 17C, upon which the charging bucket 27A is suspended by the bale 42. The inside boom member 17B is provided with rollers 43, which are adapted to ride on L track member 44, which are suspended from the ceiling 45 of the vestibule 15A. The tracks are preferably flared apart at the entrance end of the vestibule to serve as a guide for the boom, as it enters the vestibule, carrying the charging bucket 27A.

The bucket 27A is provided with a tilting bottom 28A mounted on the pivot 29A, and tilting levers 31A are provided at the end of the pivot 29A so that the angular movement of the levers tilts the bottom of the bucket attached to the pivot. Tilt rods 30A are attached at the free ends of the levers 31A and extend forwardly to abut the backwall 22A and, thereby, open the bottom of the bucket for discharge of the charging material for the cupola.

The vestibule 15A is separated from the cupola proper by a vertically sliding door 32A which operates in the slot 48 in the ceiling 45 of the vestibule, side slots 46 being also provided in the vestibule walls to guide and seal the door. This sliding door 32A is actuated by means of a chain 39, which is mechanically operated by means not shown.

The operation of the alternative form of my charging device which is shown in Figs. 4 to 7, will be apparent from the description. When it is desired to introduce a bucket containing the charge for the cupola, the boom 17 holding the bale 42 of the bucket 27A on the extension 17C of the boom is advanced into the vestibule 15A after the vestibule door 18A has been swung down to the horizontal position as shown in broken lines on Fig. 4. The vestibule door 18A is then closed, the notch 40 permitting the complete closing of the door around the boom and the sealing flange covering the opening of the notch around the boom. The closing door 32A, which has been in the closed position is then raised by means of the chain 39, the door operating in the slot 48 in the top or ceiling of the vestibule 45. The inside telescoping member 17B of the boom 17 is then advanced with rollers 43, riding on the track members 44 until the charging bucket 27A is in the cupola in the position shown in Fig. 4, the bottom of the bucket having been tilted to the open position by the tilting rods 30A, actuating the levers 31A. The charging bucket is then withdrawn by the boom into the vestibule, the closing door 32A is lowered into the position to seal off the cupola from the vestibule, the vestibule door 18A is opened, and the boom with the empty bucket is withdrawn.

My charging device is particularly adapted for use on a closed top cupola having an off-take for the discharge of gases, which off-take would generally be located above the position of the charger on the cupola. The advantages of my vestibule charging arrangement for cupolas, particularly gray iron cupolas, is that existing cupolas may be readily changed by the addition of the vestibule, and further it is possible to use existing mechanical charging equipment such as hoists and cranes.

I claim:

1. In combination with a cupola furnace hav-

ing a charging opening in the upper part thereof; a vestibule charger comprising a vestibule chamber having opposite end openings, the inner end opening coinciding with said charging opening, said chamber extending laterally from the said charging opening; a door at the outer end opening of said chamber; a charger car adapted to be moved alternately from said chamber to a position in said cupola furnace above the charge in said furnace, and tracks for said charger car in said chamber and extending across said cupola; said charger car being also provided on its inner edge with a closing wall adapted to close the cupola furnace charging opening when said charger car is in said vestibule chamber.

2. In combination with a cupola furnace having a charging opening in the upper part thereof; a vestibule charger comprising a vestibule chamber having opposite end openings, the inner end opening coinciding with said charging opening, said chamber extending laterally from the said charging opening, and said chamber being adapted to receive a charging bucket; a door at the outer end opening of said chamber; a charger car adapted to be moved alternately from said chamber to a position in said cupola furnace above the bed in said furnace, said car floor having openings therethrough for discharge of materials on said car; tracks for said charger car in said chamber and extending across said cupola; a trip bottom bucket adapted to be carried on said car; and means for tripping the bottom of said bucket when said car reaches a position midway in said cupola; said charger car being also provided on its inner edge with a closing wall adapted to close the cupola furnace charging opening when said charger car is in said vestibule chamber.

3. In combination with a cupola furnace having a charging opening in the upper part thereof; a vestibule charger comprising a vestibule chamber having opposite end openings, the inner end opening coinciding with said charging opening, said chamber extending laterally from the said charging opening, and said chamber being adapted to receive a charging bucket; a door at the outer end opening of said chamber; a charger car adapted to be moved alternately from said chamber to a position in said cupola furnace above the bed in said furnace, said car floor having opening therethrough for discharge of charging materials on said car; tracks for said charger car in said chamber and extending across said cupola; a trip bottom bucket adapted to be carried on said car; means for reciprocating said charger car between said chamber and said cupola furnace; and means for tripping the bottom of said bucket when said car reaches a position midway in said cupola; said charger car being also provided on its inner edge with a closing wall adapted to close the cupola furnace charging opening when said charger car is in said vestibule chamber.
